[57] CLAIM

The ornamental design for an automatic paint colorant dispenser, substantially as shown.

DESCRIPTION

FIG. 1 is a front perspective view of an automatic paint colorant dispenser showing my new design;

FIG. 2 is a side elevational view taken from the left of FIG. 1;

FIG. 3 is a top plan view thereof, the bottom being unornamented;

FIG. 4 is a front elevational view thereof;

FIG. 5 is a rear elevational view thereof;

FIG. 6 is a side elevational view taken from the right of FIG. 1.
